CLAIM

The ornamental design for an ultrasound applicator coupling bandage assembly, as shown and described.

DESCRIPTION

FIG. 1 is a front perspective view of an ultrasound applicator coupling bandage assembly of the present design, as viewed facing the bottom end thereof;

FIG. 2 is another front perspective view thereof, which view also shows the bottom end and right side thereof;

FIG. 3 is a rear perspective view thereof;

FIG. 4 is a front plan view thereof, oriented so that the top end faces north, the bottom end faces south, the right side faces east, and the left side faces west, where north, south, east, and west correspond to the four cardinal directions of a compass in standard plan view;

FIG. 5 is a bottom end view thereof;

FIG. 6 is a right side elevation view thereof;

FIG. 7 is a top end view thereof;

FIG. 8 is a left side elevation view thereof; and,

FIG. 9 is a rear plan view thereof.
